UNITED STATES PATENT OFFICE.

JOHN K. RIDDLE, OF TOLEDO, OHIO, ASSIGNOR TO THE EDWARD N. RIDDLE COMPANY,
OF TOLEDO, OHIO, A CORPORATION OF OHIO.

LIGHTING FIXTURE.

Application filed October 28, 1924. Serial No. 746,290.

My invention relates to that class of lighting fixtures known as chandeliers, and has for its object to enable the production of a chandelier without the necessity of any machine work thereon, and thereby enabling the production of more artistic and beautiful fixtures without the necessity of increasing the cost of manufacture and consequent cost to the purchasing public.

10 My means of accomplishing the foregoing objects may be more readily comprehended by having reference to the accompanying drawings which are hereunto annexed and are a part of this specification in which:

15 Fig. 1 is a fragmentary detail view taken from the top of a chandelier constructed in accordance with my improvement, part of the device being shown in section.

Fig. 2 is a side elevation of a chandelier embodying my invention partly shown in section for the sake of clearness.

Fig. 3 is a detail view of the conoidal body cover.

Fig. 4 is a side view of the same partly broken away to show the construction.

Fig. 5 is a fragmentary detail view of the lower end of the loop.

Fig. 6 is a top sectional view of the same.

Similar reference numerals refer to similar parts throughout the entire description.

As shown in the drawings, the chandelier comprises a spider 1, which is provided with a plurality of outwardly extending arms 2, at the extremity of which may be mounted the electric lights (not shown). In the central part of the spider are cast two screws 3 and 4, by casting them in place the need of drilling and tapping the holes is avoided. A conoidal cap 5, which forms the body of the fixture and also acts as a cover to cover up the rough parts of the castings, is provided. This cap 5 is cast with two slots 6 and 7, and two diametrically opposite grooves 17 and 18 are cast in the cap 5 leading from the slots 6 and 7 to the top of the cap 5. The cap 5 also has recesses 8 and 9 formed in its lower edge. These recesses register with and are fitted to lugs 10 and 11 cast or formed on the spider. The chandelier is suspended by means of a loop 12, the lower end of which is bifurcated, as clearly seen in Fig. 5, and the two forks 13 and 14 are provided

with circumferential slots 15 and 16. 55 These slots are fitted to the body or threaded portion of the screws 3 and 4 but are smaller than the heads thereof.

The fixture is assembled in the following manner: The conoidal cap 5 is placed on 60 the spider so that the recesses 8 and 9 register with the lugs 10 and 11 which obviously prevent its rotation. The forks 13 and 14 of the loops 12 are then placed in the radial grooves 17 and 18 formed in the side 65 walls of the conoidal cover or cap. As stated these grooves lead to the slots 6 and 7. The loop 12 is then fitted down over the conoidal cover 5, when, by tightening the screws 3 and 4 the loop is secured firmly in place and is prevented from slipping from under the screw heads by means of the lugs 10 and 11 engaging the recesses 70 cast in the rim of the conoidal cover or cap 5. This construction greatly facilitates 75 the casting of the parts.

It is thus apparent to persons skilled in the art that the entire fixture can be manufactured without the least necessity of any machine work thereon, and yet there is no 80 part of the invention which necessitates the employment of any specific design for the chandelier, hence it will be understood that although I have described a specific form of construction and illustrated the same, and 85 have even termed the one part thereof the "spider", it will be readily apparent that this showing and term is only for the purpose of illustrating a concrete embodiment of my invention, but that the same is not 90 limited thereto, and I do not wish to be so understood, as a very wide variety of designs can be employed without deviating from my invention as hereinafter claimed.

Having described my invention, what I 95 regard as new and desire to secure by Letters Patent of the United States is:

1. A lighting fixture comprising a spider, having a plurality of radiating arms, screws cast in said spider, a loop by which said spider is suspended, there being circumferential slots in the lower ends of said loop which engage said screws, lugs formed on said spider, a conoidal body cover mounted on said spider, there being slots in said cover and diametrically opposite grooves which fit the lower ends of said loops and lead from the top of the conoidal piece to said slots,

there being recesses formed in said cover which register with said lugs for the purpose set forth substantially as described.

2. A lighting fixture comprising a spider, 5 having a plurality of radiating arms, screws cast in said spider adjacent the center, a supporting member having open ended circumferential slots therein which engage said screws and means which engage said support 10 to prevent a rotative movement thereof.

3. A lighting fixture comprising a spider, having a plurality of radiating arms, screws cast in said spider, a loop, the lower part of which is bifurcated, each fork at its lower 15 end having a circumferential slot therein, a conoidal cover mounted on said spider, lugs cast on said spider which engage recesses

formed in the edge of said cover, whereby a counter clockwise movement of said loop is prevented, there being slots in said cover 20 and grooves extending to said slots in which the forks of the loop are mounted.

4. A lighting fixture comprising a spider, screws cast in said spider adjacent the center, a loop having circumferential slots in the lower end thereof which engage said screws, lugs formed on said spider, a conoidal cover mounted on said spider having recesses which engage said lugs, the end of said loop being fitted to said cover, to prevent the disengagement of the circumferential slots of the loop with said screws. 25 30

JOHN K. RIDDLE.
